Theodore L. Feinberg, Chicago, Ill., assignor to
J. & S. Manufacturing Co., Chicago, Ill.

Application April 23, 1953, Serial No. 24,642

Term of patent 14 years

(Cl. D21—1)

To all whom it may concern:

Be it known that I, Theodore L. Feinberg, a citizen of the United States and resident of Chicago, in the county of Cook and State of Illinois, have invented a new, original, and ornamental Design for a Window Shade Combined Guard and Handle, of which the following is a specification, reference being had to the accompanying drawing, forming a part thereof.

Fig. 1 is a front elevational view of a window shade combined guard and handle showing my new design;

Fig. 2 is a top plan view of the same;

Fig. 3 is a bottom plan view of the same; and
Fig. 4 is an end elevational view of the same.

I claim:

The ornamental design for a window shade combined guard and handle, substantially as shown.

THEODORE L. FEINBERG.
